CLAIM

The ornamental design for a decorative Christmas tree item holder, as shown and described.

DESCRIPTION

FIG. 1 is a perspective view of a decorative Christmas tree item holder showing my new design;

FIG. 2 is a front view thereof;

FIG. 3 is a right view thereof;

FIG. 4 is a rear view thereof;

FIG. 5 is a left view thereof;

FIG. 6 is a top view thereof; and,

FIG. 7 is a bottom view thereof.

Broken lines shown in the drawings illustrate unclaimed matter, form no part of the claimed design, and are provided for context only.
